(57) **CLAIM**

The ornamental design for a mini-charger with key chain, as shown and described.

DESCRIPTION

FIG. 1 is a perspective view of the present invention;
FIG. 2 is a perspective view of the present invention;
FIG. 3 is a front view of the present invention;
FIG. 4 is a back view of the present invention;
FIG. 5 is a side view of the present invention;
FIG. 6 is a side view of the present invention;
FIG. 7 is a top view of the present invention; and,
FIG. 8 is a bottom view of the present invention.
